UNITED STATES PATENT OFFICE.

DAVID W. HAWKSWORTH, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,385,617.

Specification of Letters Patent. Patented July 26, 1921.

Application filed August 30, 1918. Serial No. 252,901.

To all whom it may concern:

Be it known that I, DAVID W. HAWKSWORTH, a citizen of the United States of America, residing at Detroit, in the county 5 of Wayne and State of Michigan, have invented certain new and useful Improvements in Car-Roofs, of which the following is a specification, reference being had therein to the accompanying drawings.

10 The invention relates to car roofs of the all-steel type and is particularly adapted for use in car roofs of that type in which the ridge purlin is arranged on top of the carlines and in which the roofing sheets are 15 weather-proofed by carline and ridge caps, which are in turn weather-proofed by junction caps held in place by bolts having heads extending thereabove. One object of the invention is to obtain a construction in 20 which a truss is formed for the central portions of the carlines. Another object of the invention is to obtain a construction in which the running-board saddle forms this truss.

25 A further object of the invention is to obtain a construction forming a truss for the carlines which extends substantially from eaves to eaves of the car roof. Still another object of the invention is to obtain a construction in which the carline caps and the 30 means for securing the running-board saddles to the carlines can be assembled and secured together prior to their assembly in the car roof. A still further object of the invention is to obtain a construction in which 35 the heads of the bolts extending above the junction caps are weather-proofed by the running-board saddle so that any water falling upon the running board saddle will be discharged without the confines of the bolt 40 heads. Still other objects of the invention reside in the novel arrangements and combinations of parts as more fully hereinafter set forth.

In the drawings:

45 Figure 1 is a perspective view of a car roof embodying my invention, with parts broken away;

Fig. 2 is a transverse sectional view therethrough;

50 Fig. 3 is a plan view of the running board saddle;

Fig. 4 is a sectional view on the line 4—4 of Fig. 3;

55 Fig. 5 is a sectional view, showing a modified construction of saddle;

Fig. 6 is a perspective view, with parts broken away, of a portion of the car roof;

Fig. 7 is a transverse sectional view through a car roof;

Fig. 8 is a diagrammatic view of the car 60 roof, showing the trussing arrangement for the carlines.

A are the carlines, B is the ridge purlin arranged upon the carlines centrally thereof, and C are the relatively-movable roofing 65 sheets having the upstanding flanges D at their sides which are weather-proofed by the carline caps E and also provided with the upstanding flanges F at the ridge which are weather-proofed by the ridge caps G. 70 H are the junction caps fitting upon the adjacent ends of the carline and ridge caps E and G respectively for weather-proofing the car roof, and I are the bolts for securing the junction caps to the carlines, the bolts extending centrally through the ridge purlin and having the exposed heads I' extend above the junction caps.

J are the running board saddles arranged in the planes of the carline caps and rigidly 80 connected near opposite ends to the carlines. A by the Z-shaped brackets K formed of pressed sheet metal and having the reinforcing side flanges K'. The shoulder bolts L extend at right angles to the base flanges 85 of the brackets K and the inclined shoulders A' upon the carlines A and are engaged at their lower ends by the nuts L' to secure the brackets rigidly in place. The upper shoulders L² upon the shoulder bolts fit tightly 90 against the carline caps E and maintain these caps and also the brackets I in fixed spaced relation relative to the carlines A. With this construction each running board saddle forms a truss for the central portion 95 of the carlines inasmuch as its ends are rigidly connected to the carlines at spaced points upon opposite sides of the ridge purlin.

With the above construction the assembly 100 of the car roof is also greatly facilitated since the carline caps E, the brackets K, and the bolts L can be assembled and secured permanently together prior to the complete assembly of the car roof.

The carline caps E are rigidly secured near the eaves to the carlines A by means of the bolts E' which are preferably also permanently secured to the carline caps. The ends of the carline caps at the ridge rest upon 110

the ridge purlin B. Due to the fact that the carline caps are rigidly secured to the carlines near the eaves by the bolts E' and also to the carlines intermediate the eaves and 5 the ridge purlin by the bolts L and due to the fact that the ridge ends of the carline caps rest upon the ridge purlin, they form an additional truss for the carlines at least to the extent of the strength of the metal of 10 the carline caps. Thus it is seen that a truss for each carline is formed extending from near the eaves on opposite sides of the car roof.

The saddles J are pressed from sheet-metal to provide plain surface portions for 15 supporting the running-boards and to provide weather-proofing means for the exposed heads I' of the junction cap bolts I. In detail, each saddle has the horizontally-extending portion M for supporting the running-boards N and is also provided with the depressed transversely-extending channels O which provide sufficient space beneath the running-boards for the heads J² of the bolts 20 25 J' securing the saddle to the brackets K. Extending longitudinally and centrally inward from the depressed channels O are the depending ribs P, which are inclined downwardly toward the center and at their inner 30 35 ends inclined sharply downward and terminate in the concavo-convex cap portion Q adapted to surround and embrace the exposed head I' of the bolt I to weather proof the same. The depending ribs P are formed by striking out the longitudinal central portions of the saddle, which also forms the elongated openings P' intermediate these depending ribs. With this arrangement the running-board saddle is greatly reinforced 40 45 and, furthermore, any moisture, cinders, or other materials which would collect upon the saddles are free to pass through the openings and off the saddles.

The cap portion Q of the running-board 45 saddles has the sides Q' extending down about the exposed head I' of the junction cap bolt to a point therebelow so that the exposed head is embraced thereby and weather-proofed and any moisture dropping 50 55 upon the cap portion will be discharged therefrom without the confines of the head.

As shown in Figs. 1, 2 and 6 the inclined shoulders A' have a flat circular face and are located longitudinally centrally of the 55 carline. These shoulders are preferably pressed in the carline and have one edge located within the plane of the outer face thereof and the opposite edge located outside of the plane. With this construction 60 the carline is not weakened in forming the inclined shoulders.

In the modified construction, as shown in Fig. 5, the running-board saddle R fits upon the centrally upwardly extending portion 65 H' of the junction cap H and over the ex-

posed head I' of the bolt I so that the running-board saddle assists the bolt in maintaining the junction cap in place and, furthermore, effectually weather-proofs the bolt.

70

What I claim as my invention, is:

1. In a car roof, the combination with a carline, and a carline cap, of a running-board saddle above said carline cap, and a connection for securing said saddle to said 75 carline, extending through said cap.

2. In a car roof, the combination with a carline, of roofing sheets above a portion thereof, carline caps for weather-proofing said sheets, a running board saddle above 80 said carline caps, and connections for rigidly securing said saddle to said carline at spaced points, said connections extending through said carline caps.

3. In a car roof, the combination with a carline, of a ridge purlin arranged upon said carline, roofing sheets above said carline and ridge purlin, weather-proofing caps for the edges of said sheets, and a running-board saddle rigidly secured to said carline upon 90 95 opposite sides of said ridge purlin.

4. In a car roof, the combination with a carline, of a ridge purlin thereupon, roofing sheets upon said carline and purlin having adjacent upstanding flanges, and carline 95 caps each secured to said carline at spaced points, one of the points being near the eaves of the car roof, said caps forming a truss for said carline for substantially its whole length.

5. In a car roof, the combination with a carline, of a ridge purlin arranged thereupon, roofing sheets upon said carline and purlin having upstanding side flanges adjacent to each other, carline caps embracing 105 said flanges and secured to said carline near the eaves of the car roof, a running-board saddle, and means for securing said running-board saddle to said carline at spaced points, said means also securing said carline caps, 110 whereby said running-board saddle and carline caps form trusses for said carline.

6. In a car roof, the combination with a junction cap, of a bolt extending therethrough, and a running-board saddle secured 115 to the car roof beyond said cap and having a portion covering said bolt.

7. In a car roof, the combination with a carline, of a sheet metal running-board saddle, a carline cap, and means for securing 120 said saddle to said carline, said securing means and cap being permanently secured to each other and forming a unit attachment between said saddle and carline.

8. In a car roof, the combination with a carline cap, of means for connecting a running board saddle to said cap, comprising a bracket permanently secured to said cap.

9. In a car roof, the combination with a carline, of a running board saddle, carline 130

caps, brackets between said saddle and carline caps, and bolts between said carline caps and carline, said brackets, carline caps and bolts being permanently secured to each 5 other and forming a unit attachment between said carline and saddle.

10. In a car roof, the combination with a carline, of a ridge purlin thereupon, and an outside truss for said carline comprising 10 weatherproofing caps secured to said carline near the eaves of the car roof and intermediate the eaves and ridge, said caps having adjacent ends resting upon said ridge purlin.

11. In a car roof, the combination with a 15 carline extending from eaves to eaves of the car roof, of a truss for said carline for substantially its whole length, said truss arranged outside of said car roof.

12. In a car roof, the combination with a 20 carline extending from eaves to eaves of the car roof, of a truss for said carline for substantially its whole length, said truss arranged outside of said car roof, and a truss for the central portion of said carline arranged 25 outside of said car roof.

13. In a car roof, the combination with a carline extending from eaves to eaves of the car roof and a ridge purlin thereupon, of roofing sheets extending from eaves to ridge, 30 and a truss for said carline comprising members for weather-proofing said sheets, extending from eaves to ridge, said members spaced above said carline and secured thereto at spaced points and having their ridge ends 35 resting upon said ridge purlin.

14. In a car roof, the combination with a

carline, of a truss for said carline, arranged outside of said roof, said truss being connected near its ends only to said carline and the portion of said truss intermediate its 40 points of connection being arranged to support a load independent of the portion of said carline intermediate the points of connection.

15. In a car roof, the combination with a 45 carline, of a running-board saddle rigidly connected at opposite ends only to said carline, said saddle being load sustaining to transmit stresses to said carline at the points of connection thereto. 50

16. In a car roof, the combination with a carline, of roofing sheets thereabove, a load-sustaining running-board saddle spaced above said weather-proofing means, and means near the opposite ends only of said 55 saddle for securing the same to said carline.

17. In a car roof, the combination with a weather-proofing cap at the ridge, of a running board saddle secured to the car roof at opposite sides only of its ridge and having 60 a portion embracing said cap.

18. In a car roof, the combination with a carline, of roofing sheets above said carline, weather-proofing caps for the edges of said sheets, a junction cap, and a running-board 65 saddle secured to said carline at opposite sides only of said junction cap and provided with a portion embracing said junction cap.

In testimony whereof I affix my signature. 70

DAVID W. HAWKSWORTH.
